MOUNTING FOR ROCK DRILLS

Fred M. Slater, Phillipsburg, N. J., assignor to
Ingersoll-Rand Company, New York, N. Y., a
corporation of New Jersey

Application August 27, 1948, Serial No. 46,500

3 Claims. (Cl. 255—51)

1

This invention relates to drilling mechanisms, and more particularly to a mounting for drilling tools of the drifter type commonly used for drilling the vertical walls of tunnels, quarries and the like.

One object of the invention is to enable the mounting to be placed in and removed from the operative position with a minimum of effort.

Other objects will be in part obvious and in part pointed out hereinafter.

In the drawings accompanying this specification and in which similar reference numerals refer to similar parts,

Figure 1 is a side elevation, partly broken away, of a mounting constructed in accordance with the practice of the invention.

Figure 2 is a transverse view taken through Figure 1 on the line 2—2 looking in the direction indicated by the arrows.

Figure 3 is a view taken longitudinally through Figure 2 on the line 3—3.

Figure 4 is a transverse view taken through Figure 3 on the line 4—4, and

Figure 5 is a view taken through Figure 1 on the line 5—5.

Referring more particularly to the drawings, the mounting, constructed in accordance with the practice of the invention, comprises a frame 20 shown as being of Y-shape the stem 21 of which carries a pointer 22 for engagement with the supporting surface 23, as for example the floor of a tunnel or drift.

The diverging arms 24 of the frame 20 are hollow to provide chambers 25 for the accommodation of plungers 26 having heads 27 and actuating surfaces 28 thereon against which pressure fluid may act for driving the plungers 26 outwardly in the chambers 25. The plungers 26 extend from the free ends of the arms 24 and also carry pointers 22 for engagement with a surface 29 lying opposite the surface 23.

The pressure fluid used for actuating the plungers 26 is conveyed to the frame by a conduit 30 which is connected to the stem 21 and has interposed therein a control valve 31. The conduit opens into a passage 32 in the stem 21 which is also in constant communication with a conduit 33 serving to convey pressure fluid from the passage 32 to a rock drill (not shown) supported by the mounting. Passages 34 lead from the passage 32 to the chambers 25 and are controlled by throttle valves 35.

Each throttle valve 35 is rotatable in a bushing 36 in the frame 20 and has a lever 37 whereby it may be manipulated. It is shaped externally

2

for sealing engagement with a tapered surface 38 in the bushing 36 and is held thereagainst by a spring 39 that seats at one end against the end of the throttle valve and at its other end against a plug 40 threaded into the bushing 36 to seal the end of the chamber 41 containing the throttle valve.

The portion of the chamber 41 containing the spring 39 is in constant communication with the 10 branch of the passage 34 leading from the passage 32 and the branch of the passage 34 leading to the chamber 25 communicates with a cavity 42 within the throttle valve through a port 43. The pressure fluid entering the chamber 41 from the 15 passage 32 flows into the cavity 42 through a port 44 and is restrained against return flow by a spring-pressed valve 45 in the cavity 42 overlying the port 44.

An additional function of the throttle valve is 20 to establish an outlet for the escape of fluid from the chamber 25. The throttle valve is accordingly provided in its periphery and in the transverse plane of the port 43 with a groove 46 that may be brought into registry with the branch of 25 the passage 34 leading from the throttle valve chamber to the chamber 25, and a passage 47 in the portion of the throttle valve carrying the lever 37 affords communication between the groove 46 and the atmosphere.

The ports and passages in the throttle valve 30 are so arranged that when the throttle valve 35 occupies the position shown in Figure 5, and in which position the port 43 is in registry with the passage 34 leading to the chamber 25, pressure fluid will flow from the chamber 41 through the port 44 and, unseating the valve 45, will flow through the cavity 42 and the branch 34 into the chamber 25 and drive the plunger outwardly to press its pointer against the supporting surface. 35 And whenever it is intended to release the pressure fluid from the chamber 25 the throttle valve 40 is rotated to bring the groove 46 into communication with the branch 34 leading to the chamber 25. The fluid may then be exhausted from the chamber through these channels and through the passage 47 to the atmosphere.

Preferably, the free end portions of the arms 24 are rigidly braced with respect to each other by a bar 48 which may be permanently affixed 50 to the arms in any well known manner, and on the intermediate portions of the arms 24 are brackets 49—50 shown as being welded thereto to support a shaft 51 which has an enlarged end 52 extending into the bracket 49 and held against rotation with respect thereto by a key 53. At the

juncture of the shaft 51 and the enlarged portion 52 is a collar 54 to seat against the side of a rocker 55 pivotally mounted upon the shaft, and on the portion of the shaft lying on the opposite side of the rocker 55 is a sleeve 56 which extends through the bracket 50 to seat against the adjacent side of the rocker 55 for clamping said rocker selectively against pivotal movement upon the shaft 51.

The sleeve is capable of a suitable degree of movement endwise within the bracket 50 and is held against rotary movement within the bracket by a key 57 and the portion of the shaft 51 projecting from the sleeve 56 is threaded and carries a nut 58 that acts against the outer end of the sleeve for pressing said sleeve against the rocker 55.

The upper surface 59 of the rocker 55 is flattened on opposite sides of the shaft 51 to provide a seat for a clamp 60 which supports a bar 61 and consists of upper and lower sections 62 and 63, respectively. The lower section 63 is connected pivotally, by a bolt 64, to one end of the rocker and the opposite end of the section 63 projects beyond the adjacent end of the rocker 55 and carries a bolt 65 and an L-shaped plate 66 on the bolt for clamping the section 63 to the rocker 55. The end surface of one leg 67 of the plate 66 seats against the lower surface of the clamp section 63 and the side surface of the other leg 68 seats against the underside of the end portion 69 of the rocker which flares outwardly on the opposite sides of the rocker and has its outer surface curved to conform substantially with the path of movement followed by the bolt 65 when the clamp 60 is swung about the pivot bolt 64.

The upper section 62 of the clamp 60 is hinged to the section 63 by a pin 70 arranged in lugs 71 at one side of the clamp sections and is forced into clamping position against the bar 61 by a bolt and nut assembly 72 at the opposite side of the clamp sections.

The bar 61 is readily adjustable endwise in the clamp 60 and carries at one end a bearing 73 which may be affixed to the bar in any well known manner and has a slot 74 extending transversely therethrough for the reception of a head 75 at the end of an arm 76 upon which it is intended to mount the rock drill. The head 75 is of cylindrical shape and of a width substantially equalling the width of the slot 74 but is rotatable within the slot to permit of the convenient positioning of the arm 76 angularly with respect to the bar 61. The head 75 is held coaxial with the bearing 73 by a bolt 77 which extends through the two and has its head 78 seating against one side of the bearing 73 and a nut 79 acting against the opposite side of the bearing for clamping the opposed sides of the bearing to the head 75.

The arrangement of the parts supported by the shaft 51 is such that the arm 76 may be swung about in a horizontal plane to either side of the bearing 73 in order to place a rock drill supported by the arm in a desired position with respect to the work. For this purpose the bar 61 may also be rotated about its axis and move axially within the clamp 60. The bar 61, together with the arm 76, may also be swung in a horizontal plane about the bolt 64 and the clamp 60 may be conveniently secured in fixed position on the rocker 55 by clamping the plate 66 thereagainst.

The entire assembly mounted upon the shaft 51 may, moreover, be readily swung about in a vertical plane for drilling holes at different ele-

vations along a working surface. This movement is imparted to the bar by a turn-buckle assembly 80 comprising a screw 81 having the usual right and left hand threaded portions for co-operation with internally threaded sleeves 82 and 83 that are, respectively, connected to pivot pins 84 and 85 in the rocker 55 and in the frame 20. The pin 84 is positioned in the free end of the rocker 55 lying on the frame-side of the shaft 51, and the pin 85 is seated in lugs 86 on the frame 20 adjacent the juncture of the arms 24.

The screw 81 is provided at its intermediate portion with suitable means for rotating it to tilt the rocker 55, as for example a ratchet wrench, only the casing part 87 and the handle 88 of which are shown.

In practice, the mounting is placed in an upright position in front of a working surface with the pointer 22 in the stem 21 engaging the surface 23, and one of the throttle valves 35 is next opened to admit pressure fluid into the associated chamber 25. Such pressure fluid will move the plunger in said chamber outwardly and press its pointer 22 against the surface 29. The frame will then remain upright without manual support and may be rocked about the pointers 22 engaging the rock surfaces to place it in the precise position desired. After the frame has been suitably positioned the other throttle valve 35 is manipulated to admit pressure fluid into the other chamber 27 to force the associated plunger outwardly and thereby drive its pointer 22 into the surface 29. In this way the mounting will be supported by three pointers, one at one end and two at the other and will strongly resist rotation about its axis when subjected to the jars, vibrations and thrusts of the rock drill.

Whenever it is intended to drill a series of holes in a horizontal plane, it is merely necessary to swing the arm 76 to the desired position about the bolt 77 and clamp the opposed sides of the bearing 73 against the head 75 for holding the arm stationary. The range of movement of the arm in this plane may be further extended by swinging the clamp 60 to either the right or left about the bolt 64. The rock drill may also be conveniently positioned for drilling holes at different elevations by merely rotating the screw 81 and thereby cause the rocker 55, together with the parts which it supports, to tilt either upwardly or downwardly about the shaft 51 to place the rock drill in the desired position.

I claim:

1. A mounting for rock drills, comprising a rock drill supporting frame having a stem, a foot piece on the stem for engagement with a supporting surface, a pair of legs integral with and diverging from the stem and each having a chamber, a shaft mounted on said legs, members mounted on said shaft for supporting a rock drill, fluid actuated plungers in the chambers and extending from the free ends of the legs for engagement with another supporting surface, and valve means in the frame for selectively controlling the supply of pressure fluid to the chambers.

2. A mounting for rock drills, comprising a rock drill supporting frame having a foot piece at one end for engagement with a supporting surface to support one end of the frame, means movable endwise in the frame and extending from the other end thereof for engagement with another supporting surface, a shaft, means on the frame to support the shaft, a rocker tiltable about the shaft, a clamp carried by the rocker,

and a turn-buckle connected to the frame and to the rocker for tilting the rocker about the shaft.

3. A mounting for rock drills, comprising a rock drill supporting frame having a foot piece and a pair of cylinders diverging from the foot piece, means movable endwise in the cylinders and extending from the free ends thereof for engagement with a supporting surface, a shaft, means on the intermediate portion of the cylinders to support the shaft, a rocker tilttable on the shaft, a clamp pivotally connected to the rocker, a rod in the clamp and adjustable endwise therein, and a turn-buckle pivotally connected to the frame and the rocker for tilting the rocker and the clamp about the shaft.
